UNITED STATES PATENT OFFICE.

JOHN HEDLEY NICHOLSON, OF DUBLIN, IRELAND, AND WALTER SYDNEY ROBERTS, OF ORMSKIRK, ENGLAND, ASSIGNEES OF ONE-THIRD TO THE RAILWAY SIGNAL COMPANY LIMITED, OF LONDON, ENGLAND, A BRITISH COMPANY.

RAILWAY POINT, SIGNAL, AND THE LIKE.

Application filed July 21, 1924, Serial No. 727,215, and in Great Britain July 23, 1923.

This invention relates to the operation of railway points, or switches, and signals and the like, and has for its object to provide improved arrangements for this purpose whereby greater economy in installation and operation may be obtained.

In modern railway practice it is becoming increasingly necessary for economical and other purposes to operate railway switches, signals and the like at greater distances from the signal cabin or other point of control than has hitherto been the case, principally for the purpose of enabling intermediate signal cabins or points of control to be dispensed with. For this purpose electric operation of the switch and signal mechanism offers many advantages but involves either the installation of power transmission circuits to the various points on the track from a central source of power, or the provision of primary or secondary batteries. The initial cost of installing such power transmission circuits throughout the line is obviously considerable, while the maintenance of the relatively large number of batteries required particularly in outlying districts is a serious disadvantage, although an extended use of such batteries for this purpose is now being made.

According to the present invention, however, a hand or foot operated electric generator is provided at the signal cabin or other point of control for a section of the track and constitutes a source of energy for operating the various electrically actuated devices such as switch and signal motors for this section, the generator being rendered operative only when the actuation of a switch, signal, or other mechanism is required.

It will thus be seen that the advantages of electric operation are secured without the necessity for the continuous generation of electric energy or the provision of transmission conductors extending throughout the system, while the cost of maintenance is greatly reduced as compared with systems involving primary or secondary batteries.

The invention is illustrated by way of example in the accompanying drawings, of which:

Figures 1 and 2 are views in side and end elevation respectively of a hand operated generator mechanism embodying one form

of the invention, and adapted for operating electrically actuated signal or switch mechanism;

Figures 3 and 4 are views in side elevation and plan respectively of a different form of generator mechanism.

Figure 5 is a diagrammatic view showing one form of interlocking apparatus to which energy is supplied by the generator mechanism.

Figures 6 and 7 are fragmental views illustrating two modifications of the switch contact operating mechanism 15.

Similar reference characters refer to similar parts in each of the several views.

Referring now to the construction shown in Figures 1 and 2, it will be seen that the mechanism comprises a frame 1, in which is mounted an electric generator 2, of any suitable type, the shaft 3 of the generator 2 being provided with a pinion 4 mounted in a gear box 5 secured to the frame 1. The pinion 4 is adapted to intermesh with a gear wheel 6 rigidly mounted upon the same shaft 7 as a pinion 8 which intermeshes with a gear wheel 9 mounted upon a shaft 10 in the upper part of the gear box 5. The shaft 10 is provided with a crank handle 11 by means of which the shaft 3 of the generator 2 is driven through the train of gearing above described.

A number of control levers 12 is provided in the upper part of the frame 1 of the mechanism, each of these control levers when suitably adjusted, serving to operate switch contacts controlling the circuit to which the current generated by the generator 2 is supplied.

The principles of the invention may also be applied to any systems of operating switches, signals or other analogous apparatus of the kind hitherto operated by current obtained from primary or secondary batteries, such, for instance, as systems in which the supply of current to the motor operating the apparatus is controlled by a relay, the circuit of the energizing winding of which includes contacts on a lever or other control device which when it moves from its normal position towards its release position is temporarily checked by means of an electric lock, this lock being only released when the electrically actuated switch, signal or other mechanism has been fully operated.

The shaft 3 of the generator 2 is provided as indicated at 13 with a speed governor device of any suitable type, so arranged that when the operator has caused the shaft 3 to attain a predetermined speed of rotation by the actuation of the crank handle 11 the governor device 13 operates a rod 14 connected to a switch contact operating mechanism 15 which serves to connect a braking resistance in series in the circuit of the generator 2, so as to prevent any further increase in the current supplied to the electrically actuated point or signal mechanism.

Referring to Figure 6, the mechanism 15 comprises a contact lever 30 pivoted at point 31 and arranged to be swung by rod 14 into engagement with one of the fixed contact members 32. These members are connected with spaced points on a resistor 33. The lever 30 is connected with one terminal of generator 2, and one extremity of the resistor 33 is connected with the load to which current is supplied by the generator. As the speed of the generator increases, rod 14 moves toward the left, thereby swinging the lower end of lever 30 toward the right and connecting increasing amounts of the resistor 33 in series with the generator.

Alternatively, the mechanism 15 may be arranged under the same conditions to connect the braking resistance across the terminals of the generator 2, so as to impose a load upon the generator which will prevent the operator from substantially exceeding the predetermined speed of rotation of the generator shaft 3.

In Fig. 7, for example, as rod 14 moves toward the left in response to an increase in the speed of the generator the resistor 33 is connected in parallel with the generator 2 and the load. As the speed increases still further, portions of the resistor 33 are cut out, and it follows that the shunting effect of the resistor prevents an excessive supply of current to the load.

In operation it will be understood that when the operator desires to set a signal or points the appropriate control lever 12 is first adjusted to a corresponding position and the crank handle 11 is then operated to supply current to the circuit selected by the actuation of the control lever 12. It will be understood that the several control levers 12 are interlocked with one another in the usual manner so as to prevent conflicting signals or point settings from being operated, and a separate control lever 12 will preferably be provided for each signal or set of signals or points as well as for each train stop, crossing gate, token instrument, or other mechanism or apparatus controlled from the signal cabin.

In the case of electrically actuated signal mechanism as soon as the signal arm has been fully set, its operating motor may be

arranged to be cut out and the signal arm held in the position to which it has been moved by current supplied from a small local battery, the circuit of which includes an electrically actuated retaining device for 70 the signal.

The return of the control lever 12 to its normal position may be arranged to interrupt the circuit of the retaining device above referred to, thus permitting the signal to 75 return to its normal or "danger" position. The invention may also be applied to track circuit signalling systems operated by direct or alternating current which may be arranged to be supplied to the track rails 80 of a block section at any suitable point therein, a relay being connected across the track rails and adapted, when energized, to complete the circuit leading from the generator to the electrically actuated signal 85 mechanism. In the event of the track section being occupied by a train or vehicle the relay will evidently be short-circuited and consequently deenergized, with the result that the circuit leading to the signal mechanism will be interrupted at the relay contacts, so that even if the generator be operated the setting of the signal will be prevented.

Referring now to Fig. 5, the reference characters *x* and *y* designate the track rails of a stretch of railway track A—C, which is provided with a passing siding E connected with the stretch A—C by means of a switch K. Located adjacent the switch 100 K is a traffic governing device here shown as a signal S which may be of any suitable form and in the form here shown comprises two semaphore blades 54 and 55, each arranged to occupy a stop or a proceed position.

The signal S is arranged to govern traffic moving from left to right over the switch K, blade 55 being operated to give a proceed indication for traffic into the siding E, and blade 54 being operated to give a proceed indication to traffic past switch K along stretch A—C.

The rails adjacent the switch K are included in a track circuit which is supplied 115 with current from a suitable source of energy such as a track battery Q. This track circuit includes also a track relay J connected across the rails adjacent the left-hand end of stretch A—C. It will be plain 120 from the drawing that relay J is energized only when stretch A—C and siding E are all unoccupied.

The switch K may be operated by any suitable means not shown in the drawing. 125 Associated with this switch is a circuit controller F, the position of which corresponds at all times with the position of the switch. For example, when switch K is normal to permit traffic to proceed along stretch A—C,

contact 34-34^a of circuit controller F is closed, but when switch K is reversed to permit traffic to pass from stretch A-C into siding E, contact 34-34^b of circuit controller F is closed.

Associated with blade 55 of signal S are two circuit controllers G and H similar to circuit controller F and operated in accordance with the position of the blade 55. The 10 blade 54 of signal S controls two other circuit controllers T and V which are also similar to circuit controller F.

The signal S is controlled by a lever 12 which may be any one of the levers 12 shown 15 in Figs. 1 and 2 of the drawings. The lever 12 is capable of assuming a plurality of different positions indicated by broken lines in the drawing, and designated by the reference characters L, B, N, D and R. Associated with the lever 12 are a plurality of contacts designated by letters which correspond to the lever positions for which the corresponding contact is closed. For example, contact R is closed only when the lever 20 12 is in the R position. Similarly, contact LB is closed when lever 12 is in the L position, the B position or any position intermediate these two. A locking segment 44 provided with a lug 44^a is also attached to lever 25 12. Associated with the segment 44 is a locking dog 45 controlled by a magnet 46, and so arranged that lever 12 is prevented from moving from the D position or the B position to the N position, unless magnet 46 30 is energized.

Energy is supplied to the signal S for operating the semaphore blades 54 and 55 from the manually operated generator 2. For example, I will assume that it is desired to 10 permit traffic to move along the stretch A-C past switch K. In order to operate blade 54 of signal S, lever 12 is moved to the R position. The dog 45 and segment 44 do not interfere with this movement of the lever 12. 15 With the lever in the R position, a circuit is completed from generator 2 through wire 35, contact R of lever 12, wires 36 and 37, front contact 38 of relay J, wire 39, contact 34-34^a of circuit controller F, wire 40, operating mechanism of blade 54, and wire 41 back to generator 2. This circuit is closed only when circuit controller F occupies the position corresponding to the normal position of switch K, and when relay J is energized. 20 With lever 12 in the R position, then, if crank handle 11 is operated to drive generator 2, current is supplied to the operating mechanism of blade 54 over the circuit just traced. Blade 54 then moves to its proceed position. It is necessary, however, to maintain the supply of energy to the signal to 25 keep it in its proceed position. It would be undesirable to require the operator to continue operation of generator 2 for this purpose. In order to supply the small amount

of energy necessary to maintain the signal in its proceed position once it has been moved to that position, I provide a small battery P. For example, the retaining circuit for blade 54 may be traced from battery 70

P, through wires 42 and 35, contact R of lever 12, wires 36 and 37, front contact 38 of relay J, wire 39, contact 34-34^a of circuit controller F, wire 40, operating mechanism of blade 54, wire 41, contact 34-34^b of circuit controller V, and wire 43 back to battery P. It should be observed that the retaining circuit for the signal is complete 75

only if the signal has been moved to its proceed position by some other means. In order 80 to return the apparatus to its normal position, the operator moves lever 12 toward its N position. The lever is arrested at its D position, however, by engagement of dog 45 with shoulder 44^a. When the lever was 85 moved from its R position the retaining circuit for blade 54 was opened. This blade therefore returns to its stop position. When blade 54 has reached its stop position, circuit controller T is closed, and a circuit is therefore completed from generator 2 through wires 35 and 47, contact RD of lever 12, wires 48 and 49, circuit controller T, wire 50, circuit controller G, wire 51, magnet 46 and wires 52 and 41 back to generator 2. If crank handle 11 is now operated to drive generator 2, current is supplied to magnet 46 over the circuit just traced, thereby lifting the dog 45 out of engagement with the shoulder 44^a and permitting the lever 12 to be returned to its N 90 position.

In similar manner when the lever 12 is moved to the L position, contact L on the lever is closed and if generator 2 is then operated, current is supplied to the operating mechanism of blade 55 provided switch K is reversed and relay J is energized. Blade 55 then moves to its proceed position. After the blade 55 has reached its proceed position 105 it is maintained in such position by current from battery P, over contact L of lever 12, from contact 38 of relay J, circuit controller F and circuit controller H. When the lever is again moved toward its N position, it is locked in the B position until circuit controller G closes due to the return of blade 55 to its stop position. If generator 2 is then operated current supplied to magnet 46 lifts the dog 45 and permits the lever to be returned to its N position.

Although we have here illustrated the generator 2 supplying current to interlocking apparatus comprising trackway signals, our invention is not limited to this application but is equally applicable to any other form of railway traffic controlling device.

It should be particularly pointed out that the energy supplied to the apparatus for locking the lever 12 and for operating the 130

signal S is all delivered by generator 2, the battery P being used only to supply the comparatively small amount of power necessary for maintaining the signal blades in their operated positions.

In the case of electrically actuated switches, the current supplied from the manually operated generator 2 may be directly transmitted to the switch motor through circuits controlled by the setting of the control levers 12 without the use of any retaining mechanism.

Referring now to the different form of construction shown in Figures 3 and 4, it will be seen that the shaft 3 of the generator 2 is, as in the construction previously described, connected to a shaft 10 through a train of speed reduction gearing indicated at 4, 6, 8, 9. The shaft 10 is mounted in suitable bearings 16 in an horizontal frame or base plate 1, and carries at one end a bevel pinion 17 adapted to intermesh with a bevel gear wheel 18 rigidly mounted upon a short vertical shaft 19. Also rigidly secured to the shaft 19 above and below the gear wheel 18 is a pair of ratchet wheels, the upper one of which is indicated at 20 in Figure 4. The teeth of the two ratchet wheels are inclined in opposite directions and each ratchet wheel is arranged to be engaged by a number of spring actuated pawls 21 mounted in rotatable collars 22, 23, these collars being loosely mounted upon the shaft 19. A lug 24 on the upper collar 22 is pivotally connected by a rod 25 to a suitable point in a hand lever 26 above the pivot 27 of the lever 26, the lower collar 23 being similarly connected by a rod 28 to a point in the lever 26 below the pivot 27.

In operation, it will be understood that by imparting a rocking or to-and-fro movement to the lever 26 the operator is enabled to effect the continuous rotation of the shaft 3 of the generator 2 in the same direction, the bevel gear wheel 18 being driven alternately by the collar 22 and by the collar 23.

In other respects the operation of the mechanism is similar to that already described.

The generator mechanism above described may obviously with suitable modifications be arranged to be operated by the foot instead of by hand, suitable pedals or platforms being, for instance, provided for actuating the lever 25, the operator transferring his weight from one pedal or platform to the other so as to impart a to-and-fro movement to the lever 25.

Various modifications in the operating mechanisms above described may obviously be made. For instance, a pawl and ratchet mechanism or its equivalent may be interposed between the generator shaft and the driving gear for the purpose of preventing rotation of this shaft in the opposite direc-

tion to that for which the generator is designed. Again, the governor device 15 may be omitted, if desired, or may be arranged to actuate a mechanical or other non-electrical form of braking mechanism for the purpose of limiting the speed of rotation of the generator.

The invention may furthermore be applied to systems in which signalling or speed controlling apparatus carried on the train is arranged to be operated by induction from conductors on the track, controlling or signalling currents being supplied to the track conductors from the hand operated generator, which in this case will be an alternating current generator. Any suitable well known type of track and train apparatus and circuits may be employed in this application of the invention.

The manually operated generator provided at the signal cabin or other point of control may be of the direct or alternating current type as may be most suitable to the particular conditions to be met, and in this and other respects may be of any suitable design or construction.

The field magnet system of the generator may comprise permanent magnets or electromagnets separately excited from batteries or other suitable sources of electric current. Alternatively, a series, shunt, or compound field magnet system excited wholly or partly by the generator current may be employed and in order to facilitate the building-up of the field excitation a relay or other mechanism may be provided adapted when the generator is first started into operation to connect the field windings or portions thereof or separate field windings provided for starting, directly across the armature of the generator, the latter being only connected to the circuits leading to the point or signal mechanism when the voltage developed by the generator is sufficiently high to energize the relay fully and thus to effect this connection.

Furthermore, the operating mechanism associated with the generator 2 may include a device for storing energy as, for instance, by the raising of a weight, the compression of a spring, or by pneumatic or hydraulic pressure, the energy supplied to such devices being utilized in driving or assisting to drive the generator.

The invention is thus evidently not limited to the particular arrangements above described and illustrated which may be varied in many respects without exceeding the scope of the invention.

Having now described our invention what we claim as new and desire to secure by Letters Patent, is:—

1. In combination, a railway traffic controlling device, a manually operable generator, contact mechanism for at times connect-

ing said generator with said device, and means in circuit with the device and controlled in accordance with the speed of the generator for maintaining substantially constant the current supplied to said device.

2. In combination, two railway traffic controlling devices, a manually operable generator, a source of energy, contact mechanism for at times connecting said generator with a selected one of said devices, means controlled by each said device for at times connecting such device with the source, and locking means for said contact mechanism controlled by current from said generator and responsive to the conditions of said devices.

3. In combination with interlocking apparatus for controlling railway traffic, a manually operable generator for at times supplying current to said apparatus, and means in circuit with the apparatus and controlled in accordance with the speed of said generator for controlling the current supplied to said apparatus.

4. In combination with interlocking apparatus for controlling railway traffic, a manually operable generator for at times supplying current to said apparatus, a resistor, and means responsive to the speed of said generator for at times connecting said resistor in circuit with said generator.

5. In combination with interlocking apparatus for controlling railway traffic, a manually operable generator for at times supplying current to said apparatus, and means responsive to the speed of said generator for increasing the resistance in series with said generator as the speed of the generator increases.

6. In combination with interlocking apparatus for controlling railway traffic, a

manually operable generator for at times supplying current to said apparatus, means for limiting the current supplied to the apparatus from the generator, and a device responsive to the speed of the generator for controlling said means.

7. In combination, an electrically operated railway traffic governing device, a manually operable generator, a source of energy, and interlocking apparatus for at times supplying current from the generator to the device and for at other times supplying current from the source to the device.

8. In combination, an electrically operated railway traffic governing device, a manually operable generator, a source of energy, a lever for controlling the supply of current from the generator to the device and from the source to the device, and means responsive to current from the generator for controlling said lever.

9. In combination, two railway traffic controlling devices, a manually operable generator, a source of energy, contact mechanism for at times connecting the generator with a selected one of said devices, and means controlled by said contact mechanism and by each device for at times connecting such device with the source.

10. In combination, a railway signal, a manually operable generator, a source of energy, an interlocking lever, an operating circuit for the signal controlled by the lever and including the generator, and a holding circuit for the signal controlled by the lever and including the source.

In testimony whereof we have hereunto set hands.

JOHN HEDLEY NICHOLSON.
WALTER SYDNEY ROBERTS.
